UNITED STATES PATENT OFFICE.

RALPH E. STEPHENSON, OF INDIANAPOLIS, INDIANA, ASSIGNOR TO G. & J. TIRE COMPANY, A CORPORATION OF INDIANA.

METHOD OF MANUFACTURING INNER TUBES.

Application filed September 3, 1921. Serial No. 498,286.

To all whom it may concern:

Be it known that I, RALPH E. STEPHENSON, a citizen of the United States, residing at Indianapolis, county of Marion, and State 5 of Indiana, have invented a certain new and useful Method of Manufacturing Inner Tubes, of which the following is a full, clear, and exact description.

This invention relates to an inner tube for 10 pneumatic tires and its method of manufacture.

It is desirable to incorporate what is known as a valve base around the opening in an inner tube for the metal valve stem 15 by which it is inflated. The valve base is usually made of one or more (usually 2 or 3) plies of super-posed fabric. The tubes of green stock are formed preparatory to vulcanization in various ways but most generally and economically by rolling a sheet of the proper dimensions around a "pole" a suitable number of times and the valve base, or patch as it may be called, is generally applied to the front or first-coiled edge of the 20 sheet in such wise as to locate the base in direct contact with the "pole." Frequently, air is entrapped at or in the vicinity of the patch in this method of procedure and causes blemishes in the finished tube, it being understood of course that the side of the tube 25 that contacts with the pole is inverted and becomes the outside of the finished vulcanized article. Still further, the fabric valve base is usually apertured all or part way 30 through, before being applied to the pole and covered by coils of green stock, and during the cure this pre-formed aperture is closed by the flow of the rubber, which is under more or less pressure by an enveloping 35 cross-wrapper, consisting of a strip of fabric coiled spirally under more or less tension about the green tube on the pole. This filling of the hole, of course, rendered it necessary to punch the tube after it had been 40 cured. Punching required a strip of wood or soft metal to be inserted in the tube to prevent the punch going through both of its walls and necessitated an operation adding to the cost of production. If the reinforcing 45 valve base is applied to the outside of the coiled green tube, it is difficult, after curing, to locate the punch so as to make the hole in the exact center of the base, which is invisible, or substantially so. According

to the old methods or procedures therefor, 55 whether the patch is located so as to come to the inside or to the outside of the finished tube, an operative could not quickly and reliably punch holes through the exact center of the valve base. And still further, the pressure of the patch tends to flatten the stratum of rubber adjacent the inserted anvil so that, after punching, the rubber stratum contracts and becomes smaller in diameter than the hole through the fabric portion 60 of the valve base. Consequently, a punch was used of a size making a hole in the fabric reinforcement slightly larger than necessary. And this is obviously objectionable. 65

The present invention aims to produce a 70 new and improved tube in which the valve opening is molded therein during the cure and preferably in the center of a fabric reinforcing valve base that is vulcanized in the walls of the tube and substantially, if not completely, concealed from view. The invention also aims to permit molding the valve opening in the tube during its manufacture in a practical and economic manner, eliminating the punching operation heretofore deemed necessary and the objections consequent punching. 75

A preferred embodiment of the invention is 80 illustrated in the accompanying drawings in which:—

Fig. 1 shows a sheet of vulcanizable rubber composition about to be rolled around a pole;

Fig. 2 is a cross section of a "green" composition tube formed from a sheet by rolling 85 about a pole;

Fig. 3 is a plan view of a typical laminated reinforcing valve base;

Fig. 4 illustrates diagrammatically in 90 cross section a tube with a valve base being applied thereto and with a hole-molding-member in position, parts being spaced and enlarged for the sake of clearness.

Fig. 5 illustrates the cured and finished tube on a pole and in cross section through 95 the valve stem opening;

Fig. 6 is a section similar to Fig. 5, to one side of the valve stem opening;

Figs. 7 and 8 illustrate steps in a modified procedure.

Usually in making inner tubes, a calendered sheet 1 of suitable vulcanizable rubber composition is laid on the table and a pole

2 placed thereon parallel with one side and rolled over the sheet so as to ply it up into a tube, the latter being indicated at 3.

The reinforcing valve base may be made 5 in any suitable manner but, as shown in Fig. 3, is preferably made of a suitable number of plies of woven fabric 4 and vulcanizable rubber composition 4' of successively varied size, these plies being superposed 10 upon one another in the manner illustrated. Then preferably, the valve base, indicated generally by the numeral 5, is apertured centrally as indicated at 6.

According to the invention, and referring 15 to the present to Figs. 1 to 5, the preferred procedure is to apply the valve base 5 to the outside of the formed tube 3 and with the largest ply of the base outermost as indicated in Fig. 4.

20 The next step in the preferred procedure is to insert a hole-forming or molding member 7 in the aperture 6 in the valve base, the member 7 having preferably a sleeve or barrel portion 8 and a flange or abutment portion 9.

Then the green tube is cross-wrapped, i. e., it is completely confined in over-lapping spiral convolutions of a strip of fabric applied under more or less tension.

30 The tube thus prepared for curing is introduced in a steam heater, or otherwise treated, to completely vulcanize it. During the cure, the rubber softens and the hole-forming-member 7 is projected therethrough.

35 Preferably, but not necessarily, the hole-forming-member 7 is provided with a bevelled cutting edge 8' for facilitating its movement through the stock.

40 After curing, the wrapper is removed and likewise also the member 7. Then the cured tube is stripped from the pole, its ends spliced together, and a valve mounted in the opening that has been molded in the tube, all in a manner well-known to those skilled 45 in the art.

In the foregoing, the preferred method 50 of procedure has been outlined. By locating the fabric valve base so that it is located on the inside, or at least nearer the inside than the outside, of the finished tube, there is less likelihood of the product being blemished and the reinforcing or stiffening fabric 4 is disposed more advantageously. By molding the hole for the valve stem, not only is 55 the necessity of punching the tube avoided, but the walls in the opening 6 are smoother and the cut edges of the fabric better protected. It may be noted that the short plug of rubber that lies, or forms, within the barrel 8 may be readily removed on withdrawing the member 7.

The method of procedure may be varied 60 in detail without departing from the principles of the invention. While not as desirable, the patch 5 might be applied to the

pole directly and covered over by coiling the tube stock thereabout as has been the practice. In such case, with a little more time and care, the hole-forming-member 7 might be located in alignment with the hole 6 in the base and projected through the stock during the cure by the action of the wrapper as before described. But this is obviously not as desirable as the preferred procedure described. Alternatively also, 70 the patch might be incorporated between convolutions of the green tube stock as illustrated in Fig. 7, and the hole-forming-member 7 positioned and projected through the layer of rubber over-lying the aperture 75 in the valve base so as to imbed itself in the underlying convolutions of green stock. In this case also, when the wrapper is applied under tension and the tube is introduced into a heater, there will be substantially the same molding action as occurs in the preferred procedure that has been described in detail.

80 The form of the hole-forming-member may be varied. For instance, as shown in Figs. 7 and 8, it may be a disk or plug 10. In this form, after plying up the green rubber sheet on the pole with the reinforcing valve base preferably but not necessarily intermediate convolutions thereof, the hole-forming-member 10 may be pressed upon the outlying thin layer or layers of rubber covering the hole 6 and in such a way as to carry the same against the underlying convolutions of green stock, as diagrammatically illustrated in Fig. 7. The cured product, before removal of the hole-molding member 10, is illustrated in Fig. 8. The thin layer, or film, of vulcanized rubber 11 underlying the member 10 (which may be 90 made very thin by increasing the thickness of the plug 10) may be pressed out in the removal of the member 10, or cut or broken as desired (with the introduction of the valve stem, for instance).

95 These and other changes in the details of the invention are contemplated and reference should, therefore, be made to the appended claims for an understanding of the scope of the invention.

110 Having thus described my invention, what I claim and desire to protect by Letters Patent is:

1. A method of making inner tubes for pneumatic tires which consists in forming 115 a tube from vulcanizable rubber composition, rolling a sheet of vulcanizable rubber composition about a pole, making a laminated reinforcing valve-base of superposed plies of fabric successively varied in size 120 to form a skived margin, aperturing the reinforcing valve-base centrally, securing the reinforcing valve-base to the formed composition tube with its widest ply outermost, introducing a flanged sleeve in the 125

opening in the reinforcing valve-base and holding it in place, curing the tube thus formed, removing the flanged sleeve and splicing the ends of the tube.

- 5 2. A method of manufacturing inner tubes for pneumatic tires which consists in sheathing a pole with vulcanizable rubber composition, applying a reinforcing valve-base to the exterior of the composition tube, 15
10 inserting a hole-forming-member in the tube

through the center of the reinforcing valve-base, confining the tube and hole-forming-member, vulcanizing the tube, removing the tube from the pole and turning it inside out, splicing the ends of the tube, and finally mounting a valve in the hole thus formed therein.

Signed at Indianapolis, this 31st day of August, 1921.

RALPH E. STEPHENSON.
